LAST CENTERING DEVICE

Louis W. Reinhardt, Brockton, Mass., assignor
to George E. Belcher Company, Stoughton,
Mass., a corporation of Massachusetts

Application February 13, 1935, Serial No. 6,395

21 Claims. (Cl. 144—278)

This invention relates to improvements in last centering devices for use in marking the turning axis of lasts that have been reblocked for remodeling.

In recent years, the problem of remodeling lasts has become of increasing importance because of the economies permitted. As most style changes occur in the fore part of a shoe, remodeling of a last may be effected by adding stock where needed to the fore part by wedges or blocks.

In my co-pending application, Serial No. 699,570, filed November 24, 1933, I have shown my solution of the problem by cutting the outmoded last along the waist line and replacing the removed portion of the fore part by firmly securing a block of wood of sufficient size to provide for the dimensions of the new model. It is the marking of the turning axis on such reblocked lasts in which the reblock effects this replacement of the ball zone that gives rise to the problem which my present invention solves.

I am aware that various centering devices have already been made for use in last making. Most of these have been designed to hold the last in position to receive the center punches, and to effect this support, both vertical and lateral, has generally been provided for the heel and toe zones.

In accurately marking the turning axis on lasts reblocked forwardly of the waist line where no accurate basis of support is available for the fore part of the last, the devices of the prior art have no utility except for preliminary purposes. These preliminary adjustments follow the analysis of necessary last support shown in the patent to George Clausing, No. 1,052,217.

The particular problem that I had to solve had its origin in the fact that with lasts reblocked forwardly of the waist line the only available finished surfaces were rearwardly of the waist line and, therefore, the lasts had to be supported rearwardly of their point of balance.

My concept contemplates an adjustable cradle for the last rearwardly of the waist line. Such a cradle is adapted to be adjusted to any style or size and includes members that are adjustable to the contours of a model last at the edges of the last bottom in the front of the heel zone and at suitable points on the sides of the last upper substantially over the intersection of the waist line with the last bottom. With these members accurately adjusted, reblocked lasts may be held by the operator with their rear parts in seated position in the cradle and accurate centering is ensured. I also contemplate mechanism so that after adjustment of the device to the style and

size of the particular model last either a right or a left last may be accurately centered.

I also provide for mechanism that permits these supports to be readily adjusted to lasts of the same style, but of different sizes. These and various other concepts and objects will more fully appear as the description of the invention is developed.

In the accompanying drawings and specification I have shown and described an embodiment 10 of my invention and have indicated the preliminary operations necessary to the accurate adjustment of my novel device.

In the drawings:

Fig. 1 is a side view of my device with a re-blocked last in position.

Fig. 2 is a plan view of my device.

Fig. 3 is a fragmentary partly sectioned view along the lines 3—3 of Fig. 2.

Fig. 4 is a fragmentary partly sectioned view 20 along the lines 4—4 of Fig. 1.

Fig. 5 is a fragmentary view along the lines 5—5 of Fig. 1 with the last removed showing the details of the temporary support shown in dotted lines in Fig. 1.

Fig. 6 is a view illustrating an adaptor for adjusting the lateral supporting means for the sides of the last to accommodate size changes.

Fig. 7 is a view of a last indicating the zones of support available for preliminary purposes, and 30

Fig. 8 is a top plan view analyzing the most suitable available points of contour to permit the reblocked last to be accurately seated.

In devices according to my invention I provide a bed 1 suitably supported by legs 2. A heel punch 35 3 is mounted a desired distance from the bed 1 in an upright 4 which is secured to the bed 1 by bolts 5 through the flange 6. Secured to the upright 4 is a plate 7 having a V-shaped notch 8 in vertical alignment with the heel punch 3. 40

I preferably form the other end of the bed 1 with a centrally disposed groove 9 to guide the slide 10 on the bottom of the flange 11 of the upright 12 which carries a suitable toe punch 13 in alignment with the heel punch 3. The groove 45 9 is slotted as at 14 to receive the bolt 15 which locks the flange 11 to the bed 1 when the upright 12 has been positioned a desired distance from the upright 4.

Between the uprights 4 and 12, the bed 1 has a center slot 16 of desired length.

In Fig. 7, I have indicated a model last L, and by arrows I have suggested areas at which vertical support can be provided for the last L, and 55

at points marked **X** I have indicated the general zones at which lateral support may be provided to hold the last **L** in the proper position. It will be noted that a wide choice is permitted in selecting the points of support both forwardly and rearwardly of the waist line **W**. As the last **L** could thus be supported in desired position, the relatively flat surface of the ball zone and the center of the heel with suitable uprights at each point were customarily used.

In Fig. 8, a last **L**¹ is shown which has been reblocked as at **B** forwardly of the waist line **W**. The sides of the block **B** may be trimmed in the rear or only one side may be cut as shown in Fig. 8. This cut is of primary value in turning the reblocked last, but it also permits the lateral supporting members to be positioned close to the turning axis. It will be noted that, forwardly of the waist line **W**, there is no available place for support except the unfinished surfaces of the block **B**. As it is undesirable to utilize these surfaces, it is necessary to provide vertical support at the points marked with a cross (**X**) and a lateral support at the points indicated by arrows so that the last **L**¹ though not supported may be accurately seated. That is, since it is not possible to support the reblocked last in balanced position as is old in the art I propose to utilize the uneven contours to ensure the proper positioning of the last and to prevent movement of a reblocked last **L**¹ after it has been seated. In order to do this, I first follow the old practice by supporting a model last in my device.

In so doing, I utilize a threaded head **17** to support the rear center of the heel of a model last **L** in desired position relative to the heel punch **3**. The threaded head **17** may be vertically adjusted in a stem **18** which is slidably mounted in a bushing **19** centrally disposed in a cross member **20** and extending through the groove **16**.

I also provide a cross plate **21** which has a centrally positioned bushing **22** extending through the groove **16** and being adapted to receive the stem **23** (see Fig. 5). The stem **23** carries a cross arm **24** upon which are slidably mounted the blocks **25** which may be clamped on to the plate **24** in desired position by the set screws **26**. The blocks **25**, which support the last bottom, carry uprights **27** adapted to provide lateral support for the model last while it is being centered.

The bed **1** is provided with grooves **28** on each side of the slot **16**. A lock pin **29** depending from the bottom of the plate **24** extends through holes **30** in the cross plate **21** into either of the grooves **28** so that the cross arm **24** will be held against rotation whether positioned for right or for left lasts.

As the model lasts **L** may be of any size and style, the threaded head **17** is longitudinally movable as the cross member **20** is clamped to the bed **1** by bolts **31** through slots **32** (see Fig. 2). After the threaded head **17** has been positioned properly, the stem **18** is adjusted vertically to any shoe size which may be assumed to be a size 8. This vertical adjustment of the rod **18** is effected by mechanism to be later described. The threaded head **17** is then adjusted relative to the rod **18** until it will support a heel so that its turning axis might be marked by the heel punch **3**.

The stem **23** is then vertically adjusted to the same shoe size (8) and the blocks **25** are adjusted until the uprights **27** are properly spaced for lateral support. The stem **23** may be then moved

longitudinally until the turning axis of the model last is in alignment with the toe punch **13**. This longitudinal movement of the stem **23** is permitted as the cross plate **21** is adjustably clamped to the bed **1** by the headed screws **31** which pass through slots **34** in the cross plate **21** and have their threaded ends engaged with recesses **33** tapped to receive them.

It is now necessary to adjust my device to receive a reblocked last **L**¹. I utilize a cross member **35** (see Fig. 3) centrally of which there is a bushing **36** extending through the slot **16** which receives the stem **37**. The stem **37** carries a cross bar **38** upon which are slidably mounted blocks **39** which may be locked to the bar **38** by set screws **40**. The bar **38** has two slots **41** and **42** through which the bolts **43** and **44** threaded through the blocks **39** extend. Below the bar **38** the bolts **43** and **44** are provided with nuts **45** between which and the blocks **39** are springs **46** adapted to keep the bolts **43** and **44** from accidentally turning.

The stem **37** may be vertically adjusted to a desired shoe size (8) by means to be later described and the bolts **43** and **44** are adjusted to bear against the sides of the last bottom in the front of the heel. (See Fig. 3.) The stem **37** may be removed and the positions of the bolts **43** and **44** may be reversed to permit centering of right lasts and to prevent its rotation the member **35** is provided with pin holes **47** to receive a pin **48** depending from the cross bar **38**.

In order to accommodate lasts of all style sizes, I provide a structure that permits the cross member **35** to be carried with the cross piece **20** in longitudinal adjustment of the cross piece **20**, but in order to accommodate extremely "freakish" lasts I also provide for the separate longitudinal adjustment of the member **35**. To do this, I provide the member **20** with a screw **49** and the bar or member **35** is provided with a nut **50** adapted to travel over the screw **49**. The member **35** is provided with a pointer **51** which is referable to a scale plate **52** attached to the bed **1** by means of bolts **53** through the slots **54** in the plate **52**.

A cross piece **55** is secured to the bed **1** for longitudinal adjustment as by bolts **55^a** through slots **55^b** in the cross piece **55** and carries a bushing **56** to receive the post **57** (see Fig. 4). The rod **57** supports a cross strip **58** to which blocks **59** and **60** are slidably secured as by the set screws **61**. The block **59** carries an upright **62** provided with a pin **63** and the block **60** carries an upright **64** provided with a pin **65**. Each of the uprights **62** and **64** is provided with vertical slots **62^a** to permit the pins **63** and **65** to be vertically adjusted. This may be effected, as is shown in Fig. 6, by forming each pin with a flange **63^a** and threading it to receive the nut **63^b**. A plurality of adaptor caps **66** having external length of different dimensions representing suitable sizes are provided for the pins **63** and **65**. A "size 8" cap is placed on each of the pins **63** and **65** and the uprights are then adjusted laterally until the caps **66** contact each side of the model last **L** (see Fig. 4).

From Fig. 4 it will be apparent that the block **B** on the reblocked last **L**¹ and varied contours of the sides of a last in this zone present serious problems. For that reason, the pins **63** and **65** are disposed sufficiently above the cross strip **58** to avoid the block **B**. As the block **B** is substantially centered in relation to the last **L**¹, it is 75

necessary for one pin 65 to be higher than the other pin 63 to contact the outer side (the lasts shown in the drawings being left lasts) of the last at a point the same distance from the last center 5 as that contacted by the cap 66 on the pin 63 on the opposite or inside of the last.

In order to define the desired points of lateral support, it is first convenient to locate them in reference to a hinged last. With a last of that 10 type, the support is provided substantially over the forward part of the hinge assembly. The first impression of a cross section through this 15 zone (see Fig. 4) is that it is extremely asymmetrical, but if analyzed it will be seen that the upper portion tends to have respective symmetry. Below that portion, while there is no suggestion 20 of symmetry, it will be noted that the outwardly sloping surfaces present a minimum departure from respective symmetry. I support a reblocked last at points giving it the effect of having respective symmetry, which points are as far forward on the reblocked last as the reblock permits at points and where minimum vertical adjustments are required to support the last laterally 25 as if having respective symmetry. These points will be found to be along that portion of the last having a relatively constant maximum width so that minimum lateral adjustments are required.

To permit the relative position of the pins 63 30 and 65 to be reversed and to hold the strip 58 from rotation, the strip 58 is provided with a pin 67 which enters either of the pin holes 68.

In order that my device may be easily adjusted to accommodate either right or left lasts, the 35 strips 58 and 38 are marked in any desired way as by L and R so that the proper position may be readily ascertained.

After these adjustments have been made, the stem 23 and supports carried thereby are 40 moved and the device is adapted to receive a reblocked last. Such a last is not held in position by the members above referred to, but they serve to define the contour so that lasts may be accurately seated in the cradle.

If lasts of the same style, but of different sizes 45 are to be centered, adjustments are made in the following manner.

Each of the bushings 19, 22, and 36 carries a plate 69 under the bed 1. Each plate 69 is formed 50 with an arm 70 to which is secured a vertical plate 71 adapted to be marked with a size scale. Each plate 69 is also provided with a stud 72 slotted as at 73 to receive a lever 74 which is 55 adapted to bear against the rounded ends 75 of the rods. The lever 74 is positioned to lie against the vertical plate 71 which is provided with an arc-shaped slot 76 through which and the lever 74 there is a bolt which with the wing nut 77 permits the lever 74 to be locked to the plate 71 to 60 hold the rod in desired position and to permit rapid readjustment to different sizes. After these readjustments, the cap 66 on the pins 63 and 65 are replaced by caps 66 of the right size.

While centering reblocked lasts in my device 65 may seem to require many adjustments when contrasted with the simple equipment needed when some part of the fore part could be supported, the adjustments are simple and accurate and my invention provides the solution of problems resulting from reblocking lasts forwardly of the waist line.

What I therefore claim and desire to secure by Letters Patent is:

1. In a last centering device, a bed, aligned 70 heel and toe center punches mounted on said bed,

a plurality of means mounted on said bed and adapted to be adjusted to the contour of a centered last rearwardly of its waist line, said contour being generally defined by lines diverging from the center of the rear portion of the heel 5 through the outer edge of the front of the heel to the sides of the upper portion substantially over the intersection of the waist line and the last bottom whereby necessary vertical and lateral support is afforded to permit lasts reblocked forwardly of the waist line to be positioned in said device and accurately centered.

2. In a device for marking the turning axis on lasts reblocked forwardly of the waist line, aligned heel and toe punches, means adapted to be ad- 15 justed to cradle the heel of a last, said means including a support for the rear center of said heel and a support for each edge of the front of the heel zone, and means adapted to be ad- 20 justed to provide lateral support for the last upper adjacent the reblock at points requiring minimum adjustment to support said last upper as if having respective symmetry.

3. In a device for marking the turning axis on lasts reblocked forwardly of the waist line, a bed, 25 aligned heel and toe punches supported a fixed distance from said bed, means mounted on said bed for longitudinal movement and adapted to be adjusted to cradle the heel of a last, said means including a support for the rear center of said heel 30 and a support for each edge of the front of the heel zone and means adapted to be adjusted to contact each side of the last upper adjacent the reblock in a zone in which the vertically sloping surfaces have customarily a minimum departure 35 from respective symmetry, said second named means comprising a cross member detachably mounted on said bed, a pair of uprights secured to said member for lateral adjustment, a pin carried in each upright, one of said pins being higher than 40 the other to overlie the outer last edge to permit said uprights to provide space for the blocked fore part, and means to adjust said pins to accommodate 45 lasts of different sizes.

4. In a device for marking the turning axis on lasts reblocked forwardly of the waist line, a bed, aligned heel and toe punches supported a fixed 50 distance from said bed, means mounted on said bed for longitudinal movement and adapted to be adjusted to cradle the heel of a last, said means including a support for the rear center of said heel and a support for each edge of the front of the heel zone, and means adapted to be adjusted to contact each side of the last upper substantially over the intersection of the waist line with the 55 sole, said second-named means comprising a cross member detachably mounted on said bed, a pair of uprights secured to said member for lateral adjustment, a pin carried in each upright; one of said pins being higher than the other to overlie the outer last edge to permit said uprights to be 60 positioned equally from the center to provide space for the blocked fore part, means to adjust said pins to accommodate lasts of different sizes, and a plurality of caps for said pins, said caps 65 being of varying external diameters to contact the sides of lasts of different sizes.

5. In a device for marking the turning axis on lasts reblocked forwardly of the waist line, aligned heel and toe punches, means adapted to be ad- 70 justed to cradle the heel of a last, said means including a support for the rear center of said heel and a support for each edge of the front of the heel zone, means adapted to be adjusted to contact each side of the last upper substan- 75

tially over the intersection of the waist line with the sole to cooperate with said first named means in aligning said lasts, and an adjustable temporary support for the fore part of a model last 5 to cooperate with said support for the rear center of the heel in determining adjustment of said second named supports and said second named means.

6. In a device for marking the turning axis on lasts reblocked forwardly of the waist line, aligned heel and toe punches, means adapted to cradle the heel of a last, said means including a support for the rear center of said heel and a support for each edge of the front of the heel zone, means 10 for vertically and longitudinally adjusting said supports, means adapted to contact each side of the last upper substantially over the intersection of the waist line with the sole to cooperate with said first named means in aligning said lasts, 15 means for laterally and vertically adjusting said upper contacting means, and a temporary support for the fore part of a model last to cooperate with said support for the rear center of the heel in determining adjustment of said second named 20 heel supports and said upper contacting means and means vertically or longitudinally adjusting said temporary support.

7. In a device for marking the turning axis on lasts reblocked forwardly of the waist line, aligned heel and toe punches, means adapted to be adjusted to cradle the heel of a last, said means including a support for the rear center of said heel and a support for each edge of the front of the heel zone, means adapted to be adjusted to 25 contact each side of the last upper substantially over the intersection of the waist line with the sole to cooperate with said first named means in aligning said lasts, an adjustable temporary support for the fore part of a model last to cooperate 30 with said support for the rear center of the heel in determining adjustment of said second named supports and said second named means, and said last named support including a portion adapted to bear against the sole of a model last and a pair of 35 laterally adjustable uprights adapted to provide lateral support.

8. In a device for marking the turning axis of lasts reblocked forwardly of the waist line, a bed, aligned heel and toe center punches mounted for 40 longitudinal movement on said bed, a plurality of means mounted on said bed and adapted to be adjusted to the contour of a centered last rearwardly of its waist line, said contour being generally defined by lines diverging from the center 45 of the rear portion of the heel through the outer edge of the front of the heel to the sides of the upper portion substantially over the intersection of the waist line and the last bottom, and means for adjusting said means to accommodate lasts of 50 different sizes.

9. In a device for marking the turning axis of lasts reblocked forwardly of the waist line, a bed, aligned heel and toe punches supported a fixed 55 distance from said bed, a plurality of means adapted to cradle a reblocked last in desired position relative to said punches, said means comprising vertical supports including a member adapted to support the rear center of the heel of a last and a pair of independently adjustable members to support the edge of the last bottom in the front of the heel zone and lateral supports for the last upper substantially over the intersection of the waist and sole lines.

75 10. In a device for marking the turning axis

of lasts reblocked forwardly of the waist line, a bed, aligned heel and toe punches supported a fixed distance from said bed, a support for the rear center of the heel of a last, a pair of supports independently adjustable to the contour of the edges of the last bottom in the front of the heel zone, said supports being detachably mounted in said bed means for longitudinally and vertically adjusting said supports, a member detachably mounted on said bed to provide lateral support for the last upper substantially over the intersection of the waist and sole lines, and means for holding said detachable members at right angles to the turning axis, whereby right and left lasts may be accurately centered by reversing said detachable members.

11. In a device for marking the turning axis of lasts reblocked forwardly of the waist line, a bed, aligned heel and toe punches supported a fixed distance from said bed, means carried by 20 said bed and being adapted to cradle a reblocked last in desired position relative to said punches, said means including a member adapted to support the rear center of the heel of a last, a pair of members to support the edges of the last 25 bottom in the front of the heel zone, means to permit said members to be independently adjusted, and supports adapted to contact the last upper substantially over the intersection of the waist and sole lines, means for longitudinally 30 and vertically adjusting said members in relation to said bed and to each other, and means adapted to permit said upper contacting supports to be vertically and laterally adjusted independently of each other.

12. In a device for marking the turning axis of lasts reblocked forwardly of the waist line, a bed, aligned heel and toe punches supported a fixed distance from said bed, means adapted to cradle a reblocked last in desired position 40 relative to said punches, said means including a member adapted to support the rear center of the heel of a last, a pair of members to support the edges of the last bottom in the front of the heel zone, means to permit said members 45 to be independently adjusted, and supports adapted to contact the last upper substantially over the intersection of the waist and sole lines, cross members adapted to receive said heel contacting members, means securing said cross members 50 to said bed and being adapted to permit the adjustment thereof longitudinally of said bed and each other, and means adapted to adjust said members vertically of said bed for lasts of different sizes.

13. In a device for marking the turning axis of lasts reblocked forwardly of the waist line, a bed, aligned heel and toe punches supported a fixed distance from said bed, means carried by 60 said bed and being adapted to cradle a reblocked last in desired position relative to said punches, said means including a member adapted to support the rear center of the heel of a last, a pair of members to support the edges of the last 65 bottom in the front of the heel zone, means to permit said members to be independently adjusted, and supports adapted to contact the last upper substantially over the intersection of the waist and sole lines, a cross member on said bed for each of said heel contacting members, means to permit said cross members to be adjusted longitudinally of said bed and of each other, a bushing in each of said cross members, a plate secured to each of said bushings, a scale 70 75

plate secured to said plate, a lever pivotally secured to said plate and extending under said bushing and against said heel contacting member, and means for locking said lever in desired 5 position to said scale plate whereby said vertical supports may be adjusted to accommodate lasts of varying sizes.

14. In a device for marking the turning axis of lasts, aligned heel and toe punches, a cradle 10 adapted to permit a last to be held in desired relation to said punches, said cradle comprising a support for the rear center of the heel, a support for each edge of the last bottom forwardly of the heel zone, a support for each side of the 15 last upper substantially over the intersection of the waist and sole lines, means adapted to permit the adjustment of said supports to contact a last of a given style, and means adapted to permit said supports to be rapidly readjusted to different sizes of said style.

15. In a device for marking the turning axis of lasts, aligned heel and toe punches, a cradle 20 adapted to permit a last to be held in desired relation to said punches, said cradle comprising a support for the rear center of the heel, a support for each edge of the last bottom forwardly of the heel zone, a support for each side of the 25 last upper substantially over the intersection of the waist and sole lines, means adapted to permit the adjustment of said supports to contact a last of a given style, and means adapted to permit said supports to be rapidly readjusted to different sizes of said style, and reversible means 30 adapted to permit said device to accommodate right or left lasts.

16. In a device for marking the turning axis of lasts reblocked forwardly of the waist line, aligned heel and toe punches, a cradle for a last, said cradle including supports for the heel zone of 40 a last bottom and guides adapted to contact each side of the last upper substantially over the intersection of the waist and sole lines, means adapted to permit said cradle to be adjusted to the contour of a model last, and means adapted to 45 permit said cradle to be readjusted to accommodate lasts of different sizes.

17. In a device for marking the turning axis of lasts reblocked forwardly of the waist line, aligned heel and toe punches, a cradle for a last, said cradle including supports for the heel zone of a last bottom and guides adapted to contact each side of the last upper substantially over the 50 intersection of the waist and sole lines, means adapted to permit said cradle to be adjusted to the contour of a model last, means adapted to permit said cradle to be readjusted to accommodate lasts of different sizes, and means adapted to 55 permit right and left lasts to be cradled.

18. Apparatus for marking the longitudinal 60 turning axis in a last comprising aligned heel and toe punches and means for positioning said last in axial alignment with said punches, including a cradle for the last adapted to support the last rearwardly of the waist line thereof, said cradle 65 comprising a support for the bottom of the last heel, and a member disposed transversely of the last carrying a pair of independently laterally and longitudinally adjustable guides adapted to be set to engage the upper of the last at opposed points

and substantially over the intersection of waist line and last bottom.

19. In a device for marking the turning axis of lasts reblocked forwardly of the waist line, a bed, aligned heel and toe punches supported a fixed 5 distance from said bed, a three point support for the heel zone of the last bottom carried by said bed and defining a triangle having its base transversely of the front of the heel zone, means adapted to permit said support to be longitudinally 10 adjusted on said bed, and the supports defining the base of said triangle to be longitudinally adjusted in relation to the other of said supports, means to permit said base supports to be independently laterally adjusted, and means to 15 permit said supports to be independently adjusted vertically of said bed, a pair of guides adapted to contact each side of the last upper substantially over the intersection of the waist and sole lines, means to permit said guides to be independently 20 adjusted vertically and laterally whereby the contour of a model last may be established rearwardly of the waist line.

20. In a device for marking the turning axis of lasts reblocked forwardly of the waist line, a 25 bed, aligned heel and toe punches supported a fixed distance from said bed, a three point support for the heel zone of the last bottom carried by said bed and defining a triangle having its base transversely of the front of the heel zone, means 30 adapted to permit said support to be longitudinally adjusted on said bed and the supports defining the base of said triangle to be longitudinally adjusted in relation to the other of said supports, means to permit said base supports to be independently 35 laterally adjusted and means to permit said supports to be independently adjusted vertically of said bed, a pair of guides adapted to contact each side of the last upper substantially over the intersection of the waist and sole lines, 40 means to permit said guides to be independently adjusted vertically and laterally whereby the contour of a model last may be established rearwardly of the waist line, and means to permit said cradle to be readjusted for different sizes of lasts 45 of like style.

21. In a device for marking the turning axis of lasts reblocked forwardly of the waist line, a bed, aligned heel and toe punches supported a fixed 50 distance from said bed, a three point support for the heel zone of the last bottom carried by said bed and defining a triangle having its base transversely of the front of the heel zone, means adapted to permit said support to be longitudinally 55 adjusted on said bed, and the supports defining the base of said triangle to be longitudinally adjusted in relation to the other of said supports, means to permit said base supports to be independently laterally adjusted and means to permit said supports to be independently adjusted vertically of said bed, a pair of guides adapted to contact each side of the last upper substantially over the intersection of the waist and sole lines, 60 means to permit said guides to be independently adjusted vertically and laterally whereby the contour of a model last may be established rearwardly of the waist line, and means to permit said base supports and said guides to be reversed to 65 accommodate right and left lasts.
